(57) **CLAIM**

The ornamental design for an ink stick for a phase change ink jet printer, as shown and described.

DESCRIPTION

FIG. 1 is a perspective view of an ink stick for a phase change ink jet printer in accordance with the present invention;
FIG. 2 is a front view thereof;
FIG. 3 is a right side view thereof;
FIG. 4 is a rear view thereof;
FIG. 5 is a left side view thereof;
FIG. 6 is a top plan view thereof; and,
FIG. 7 is a bottom plan view thereof.

The features shown in broken lines in the drawing figures depict environmental subject matter only and form no part of the claimed design
